HAIR CLIP

Oscar L. Engstrom, New York, N. Y.

Application April 15, 1949, Serial No. 87,649

10 Claims. (Cl. 132—50)

1

This invention relates to hair clips, and more particularly to a sheet metal clip having opposed prongs for holding strands of hair during curling and other hair dressing operations.

One object of this invention is to provide a clip of the above nature wherein the user may separate the prongs merely by pressing an end portion of the clip, whereby the clip may be easily applied and removed without disturbing the hair arrangement unduly.

Another object is to provide a clip of the above nature in which the prongs have both lateral and longitudinal deformations, whereby the hair will be firmly held by the resilient action of the clip.

A further object is to provide a clip of the above nature which will be simple in construction, inexpensive to manufacture, easy to use and manipulate, compact, ornamental in appearance, and very efficient and durable in use.

With these and other objects in view, there have been illustrated on the accompanying drawings two forms in which the invention may conveniently be embodied in practice.

In the drawings,

Fig. 1 is a side view of the first form of the improved hair clip.

Fig. 2 is a plan view of the same.

Fig. 3 is a side view of the second form of the hair clip.

Fig. 4 is a top plan view of the same.

Fig. 5 is a cross-sectional view on a larger scale, of the first form of the clip, taken on the line 5—5 of Fig. 2.

Referring now to the drawing in which like reference numerals denote corresponding parts throughout the several views, the numeral 10 generally indicates a hair clip which is preferably formed from sheet metal, and which comprises a resilient U-shaped loop portion 11 having a flat lower arm 12 which extends forwardly into a bifurcated jaw portion in the form of a pair of parallel upper prongs 13, 14.

The loop portion 11 also includes an upper arm 15 which extends forwardly into a jaw portion in the form of a downwardly offset central lower prong 16 which has a reduced neck 17 movably disposed between the upper prongs 13, 14, and which tapers outwardly to a broad forward end 18 overlapped by the upper prongs 13, 14.

It will be understood that the resilient loop portion 11 is so formed as to urge the lower and upper arms 12 and 15 apart, thus urging the upper prongs 13, 14 toward the central lower prong 16 so as to grip a strand of hair which may be inserted therebetween.

In order to hold the hair against slipping longi-

2

tudinally of the clip, the spaced upper prongs 13, 14 are provided with a plurality of collateral reverse bends 19 disposed in vertical planes.

Further, the gripping action of the jaw portions 5 or prongs 13, 14, and 16 is enhanced by means of longitudinal ribs 20 which are downwardly embossed in the upper prongs 13, 14, and a longitudinal rib 21 which is upwardly embossed in the central lower prong 16.

10 The ribs 20 are so disposed as to lie at opposite sides of the lower prong 16, while the rib 21 is adapted to extend upwardly in the space between the upper prongs 13, 14, as clearly shown in Fig. 5. Thus, strands of hair which may be inserted in 15 the clip 10 will be firmly held against slipping by means of the plurality of projecting ribs and edges which are provided by the prongs 13, 14, and 16.

Second form

20 The numeral 22 indicates a second form of the improved hair clip which includes a resilient loop portion 23 having a flat lower arm 24 which extends forwardly into an upwardly-inclined reduced neck 25. The neck 25 is outwardly broadened and bifurcated so as to provide a jaw portion in the form of a pair of spaced upper prongs 26, 27.

25 The loop portion 23 also includes an upper arm 28 which extends forwardly, at opposite sides of the reduced neck 25, in the form of a bifurcated jaw portion providing a pair of downwardly offset spaced lower prongs 29, 30, which are overlapped by the upper prongs 26, 27.

30 In order to exert an efficient gripping action, 35 the upper prongs 26, 27 are preferably formed with a plurality of collateral reverse bends 31, disposed in vertical planes. The gripping action of the clip 22 is further improved by means of longitudinal ribs 32 which are downwardly embossed in the upper prongs 26, 27, and longitudinal ribs 33, which are upwardly embossed in the lower prongs 29, 30.

35 It will be understood that the resilient loop portion 23 is so formed as to urge the arms 24, 28 apart, and consequently will urge the upper prongs 26, 27 toward the lower prongs 29, 30 so as to grip strands of hair which may be placed therebetween.

40 In order to reduce the weight of the hair clip 50 22, the loop portion 23 is preferably formed with a central slot 34.

Operation

45 In operation, the user will merely compress 55 the resilient loop portion 11 between her fingers so as to separate the upper prongs 13, 14 from

the lower prong 16. After the desired strands of hair have been inserted between the prongs, the pressure upon the loop portion 11 will be released, whereupon the hair will be firmly clamped between the prongs.

The second form of hair clip shown in Figs. 3 and 4 will be operated in substantially the same manner, merely by compressing the resilient loop portion 23.

One advantage of the improved hair clip herein disclosed is that it is very easy to manipulate and may be applied to the hair without danger of cracking the finger nails and without the manipulation of auxiliary catches or detents.

While there has been disclosed in this specification two forms in which the invention may be embodied, it is to be understood that these forms are shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In a hair clip, a resilient loop portion having thin upper and lower arms which extend forwardly into respective lower and upper jaw portions disposed in overlapping face-to-face, overlying engagement with each other, one of said jaw portions comprising a pair of spaced prongs, and the other of said jaw portions comprising a reduced neck movably disposed between said spaced prongs.

2. The invention as defined in claim 1, in which said jaw portions are provided with longitudinal ribs for gripping strands of hair between said jaw portions.

3. The invention as defined in claim 2, in which one of said jaw portions is provided with a plurality of reverse bends for holding strands of hair against slipping longitudinally of said jaw portions.

4. In a hair clip, a resilient loop portion having upper and lower arms, said lower arm extending forwardly into a pair of integral spaced prongs, said upper arm extending forwardly into a downwardly-offset central prong having a

downwardly-inclined reduced neck which is movably disposed between said spaced prongs, said spaced prongs laterally overlapping the upper surface of said central prong.

5. The invention as defined in claim 4, in which said central prong is provided with an upwardly-extending longitudinal rib between said spaced prongs.

6. The invention as defined in claim 4, in which said spaced prongs are provided with downwardly-extending longitudinal ribs outwardly of opposite edges of said central prong.

7. The invention as defined in claim 4, in which said spaced prongs are provided with a series of reverse bends for holding a strand of hair against slipping longitudinally thereof.

8. In a hair clip, a resilient loop portion having upper and lower arms, said upper arm extending forwardly into a pair of integral downwardly-offset spaced lower prongs, said lower arm having a pair of spaced upper prongs overlapping said lower prongs and integrally joined to said lower arm by a reduced neck which is movably disposed between said lower prongs.

9. The invention as defined in claim 8, wherein said prongs are provided with longitudinal ribs for gripping strands of hair between said upper and lower prongs.

10. The invention as defined in claim 9, wherein one of said pairs of prongs is provided with a plurality of reverse bends for holding a strand of hair against slipping longitudinally thereof.

OSCAR L. ENGSTROM.
